SUPPORT FOR BED FRAMEWORK

Edward J. Strybel, Cincinnati, Ohio, assignor to
 Campbell and Company, Cincinnati, Ohio, a
 partnership

Application July 8, 1949, Serial No. 103,635

1 Claim. (Cl. 5—294)

1

This invention relates to supports for a bed framework and more particularly to an adjustable support structure adapted to fit bed frames of various sizes and types.

Home and hospital beds come in various widths. Normally the framework of a bed is supported by head and foot boards which carry lug receiving plates that can engage lugs attached to the bed framework. However, the spacing between lugs normally varies between beds and in addition, the lug receiving plates on bed head and foot boards vary in spacing so that ordinarily the framework of a bed fits only the head board and foot board specially designed therefor.

An object of this invention is to provide a support structure for a bed framework which is adapted to be supported by head and foot boards of various widths so that the framework can be used with various head and foot boards to replace the conventional bed framework.

A further object of this invention is to provide a support for a corner of a bed framework having a pair of lugs mounted one above the other, one lug of the pair being adjustable toward and away from the other lug to accommodate lug holding plates having various lug spacing.

A further object of this invention is to provide a bed framework having side rails to which removable lug holding plates may be attached in various positions to accommodate head and foot boards of various widths, and to which separate legs may be attached, if desired, so that the bed framework may be supported without the use of head and foot boards.

The above and other objects and features of the invention will in part be obvious and will in part be apparent from the following detailed description and the drawings, in which:

Fig. 1 is a fragmentary view in side elevation showing a portion of a bed framework and a foot board having adjustable supports constructed in accordance with an embodiment of this invention;

Fig. 2 is a fragmentary plan view of the bed framework and foot board illustrated in Fig. 1;

Fig. 3 is a view in side elevation showing a gusset plate which forms a portion of the bed support;

Fig. 4 is a view in section taken along a line IV—IV in Fig. 1;

Fig. 5 is a view in section similar to Fig. 4 and showing the bed support in an alternate position;

Fig. 6 is a view in section similar to Fig. 4 and showing the bed support in another alternate position;

2

Fig. 7 is a fragmentary view in side elevation showing the bed framework supported by a removable leg;

Fig. 8 is a view in section taken along a line VIII—VIII in Fig. 7; and

Fig. 9 is a view in section showing a bed support constructed in accordance with a second embodiment of the invention.

In the following detailed description and the drawing, like reference characters indicate like parts.

In Figs. 1 and 2 a bed framework is shown which includes side rails 10 and a cross rail 11 which are attached together in the usual manner. The rails may be formed from angle irons and may be adapted to support movable bed sections, one of which is indicated at 12, and appropriate operating cranks and linkage 13 may be provided for raising and lowering the movable sections.

The side rails are equipped with bolt holes. Bolts 15 extend through the bolt holes and removably attach gusset plates 16 to the side rails, the bolts 15 extending through bolt holes 18 in the gusset plates and through the bolt holes in the side rails.

As shown in Fig. 3, each gusset plate 16 is generally trapezoidal in shape having a portion which contains the bolt holes 18 by means of which the gusset plate may be attached to one of the side rails and a second portion adapted to extend beyond the end of the side rail in which are located a vertical slot 22 and a bolt hole 23 aligned therewith. The slot 22 and bolt hole 23 are adapted to receive the shanks respectively of a stationary lug 24 (Figs. 1 and 4), and a movable lug 26. The stationary lug 24 includes a threaded end, an intermediate shank portion of larger diameter than the threaded portion, and an enlarged head, being of usual construction, and as shown in Fig. 4, the lug 24 is held in place in the bolt hole 23 by means of an appropriate nut on the threaded portion thereof with the intermediate shank and head extending outwardly from the gusset plate.

The movable lug 26 is similar in form to the stationary lug including a threaded portion, an intermediate shank of larger cross-section than the threaded portion, and an enlarged head, the threaded shank portion of the lug 26 extending through and being held in the slot 22 so that the lug 26 is movable along the slot 22 toward or away from the stationary lug 24.

As shown in Fig. 1, the lugs 24 and 26 are adapted to fit into lug holding slots 27 in a lug plate 28 attached to a foot board 29.

The stationary lugs may support substantially all the weight of the framework, while the movable lugs act as guides and hold the foot board upright preventing the foot board from turning about the stationary lugs.

Each movable lug may be moved up or down along slot 22 so that the supports may be adapted to foot boards having variously spaced slots in lug receiving plates. The foot board 29 carries two lug plates 28, as shown in Fig. 2, and a pair of gusset plates 16 are attached to the bed frame, one on either side thereof, each gusset plate being attached to one of the side rails 10. As shown in Figs. 2 and 4, the gusset plates may be attached to the outer sides of the side rails with lugs extending outwardly to adapt the bed frame to a relatively broad foot board. On the other hand, as shown in Fig. 5, the gusset plates or lugs may be reversed so that while the gusset plates are mounted on the outer sides of the bed side rails, the lugs extend inwardly to accommodate a foot board having moderately spaced lug plates.

Further, the cross rail may be cut away or slotted as indicated at 31 in Fig. 4, and the gusset plates may be mounted on inner sides of the side rails, as shown in Fig. 6, with the lugs extending inwardly to accommodate a bed having a narrow foot board.

As will be understood, a head board may be provided having lug supporting plates similar to those of the foot board and adapted to support the head end of the bed frame.

In some beds, the head and foot boards may be of such width that it is impossible to adapt the framework supporting lugs to fit the head and foot boards, and in such case, as shown in Figs. 7 and 8, separate legs may be attached to the bed side rails in place of the gusset plates 16. Each leg member includes a vertical bar or leg 31 welded or otherwise firmly attached to a gusset plate 32. As shown, the gusset plate 32 may have three bolt holes which can register with the bolt holes in the side rail so that the gusset plate 32 can be attached to a side rail with the leg 31 extending downwardly to support the bed frame.

In Fig. 9 is shown a modified form of bed support which differs from the support shown in Figs. 1 to 6 inclusive in the form of lugs. In Fig. 9 a corner of a bed framework is shown which includes a cross rail 34 and a side rail 36. A gusset plate 37 similar in form to the gusset plate 16 is attached to the side rail 36 by means of bolts 38. A pair of lugs 39 and 40 are attached to the gusset plates and can be received in lug receiving slots of a lug plate 41. The upper lug 39 is stationary and extends through a circular hole 42 in the gusset plate, while the lower lug 40 is movable vertically toward and away from the stationary lug and extends through a vertical slot 43 in the gusset plate.

Each lug, as shown, may include a threaded end extending outwardly from the gusset plate through one of the slots in the lug plate. Nuts 44 may be carried by the lugs, which nuts can be drawn up against the lug plate to give the bed framework a firm support. As can be seen from the drawings, the support illustrated in Fig. 9 can be adapted for use with a variety of bed end frameworks of various widths. As will be understood, similar gusset plates, lugs, etc. may be provided at each corner of the bed framework.

By means of the adjustable supports of this invention, a single bed frame may be supported by any of many different sizes and types of head and foot boards having lug receiving plates of various spacings and slots in the plates of various spacings, or the bed frame may be supported by itself on the legs 31 without requiring support from the head and foot boards. Thus, it is possible to construct a single movable bed frame which can be substituted for the conventional frame in any of many different types and sizes of beds.

The embodiment of the invention described above and illustrated in the drawing is subject to structural modification without departing from the spirit and scope of the appended claim.

Having described my invention what I claim as novel and desire to secure by Letters Patent is:

A bed which comprises a pair of spaced side rails, each side rail having a substantially vertical flange, a vertical gusset plate removably attached to the vertical flange of each side rail at one end thereof, each gusset plate being selectively attachable to either side of the flange with which it is associated, each gusset plate having a portion extending beyond the end of its associated side rail, said portion of each gusset plate containing a bore and a vertical slot vertically spaced from the bore, a transverse lug mounted in each of said slots and bores, each of said lugs having a portion extending outwardly from one side of the gusset plate with which it is associated and removably received in a lug holding slot of one of a pair of spaced lug holding plates attached to a bed end frame, the lug in the slot of each gusset plate being movable up and down in the slot to adjust the spacing of the lugs, so that the lugs are receivable in lug holding plates having lug holding slots of various spacings, and means for locking each movable lug in predetermined position of adjustment in its slot.

EDWARD J. STRYBEL.
